METHOD AND APPARATUS OF ROPE POLISHING CIRCULAR COMPRESSION DIES
Charles E. Nixon, 110 W. Howard St., Waveland, Ind.
Filed Sept. 16, 1964, Ser. No. 396,852
4 Claims. (Cl. 29—90)

The present invention relates to an improved method and apparatus of rope polishing compression dies useful in various industries for polishing compression dies, and more particularly relates to the endless rope connection means for arranging the rope in endless fashion as an improvement over other endless rope connecting means.

In the prior art, it has been known to provide rope polishing ropes which are connected at their ends by a two-foot cable, which may often times be longer such as 26 inches, or the like. It is known that these cables are used as the connecting means between the ends of the rope as it is formed in an endless fashion so that the two-foot cable length would therefore serve as a guide to the incoming rope end entering into the top side of the die which is to be polished. It has been found that there are numerous times when such an arrangement of the prior art adequately provides a polished surface for the compression die, but the cables used in forming the rope into an endless construction result in the total destruction of the rope ends, particularly the forward or front end of the cable, as it commences to pass through the hole to be polished in the steel die.

Therefore, an object of the present invention is to provide a new connecting or coupling means between the ends of the polishing rope after it has been threaded or passed through the apertures or openings to be polished, and to connect the ends of the rope by steel hooks without any intervening cable being disposed for such connection.

A further object of the present invention is to provide means for coupling the ends of a polishing rope so that the overall length between the ends of the polishing and working area of each of the ropes is not more than two inches, so that one rope end is allowed to polish through the die and to act as a guide for the trailing end of the rope as it enters the top side of the hole.

Other objects and advantages as well as a complete understanding of the invention may be had from the following description of a particular embodiment of the invention. In the description, reference is made to the accompanying drawings of which:

FIGURE 1 is a 3-dimensional perspective view shown in partially broken away fashion for illustrating the endless polish-rope of the invention;

FIGURE 2 shows connecting means for connecting ends of the polishing rope in the manner of the preferred embodiment of the invention; and

FIGURE 3 shows an arrangement by which a plurality of openings in a circular compression die is being polished in accordance with endless ropes being used and connected in accordance with the present invention.

Referring now to the drawings, there is shown a panel 10 that is substantially vertically positioned, although this is not a functional requirement, so that there are mounted thereon at least a pair of pulleys 12, 14, and an additional pulley 16 for passing a cord 20 over the pulleys. One of the pulleys is adapted to drive the cord 20 about the endless path so that it is continuously passed around the circuit provided by the cord. The endless rope or cord 20 passes through both a top and bottom of a compression die 22 having holes 24, 26 as particularly shown in FIGURE 3 and generally shown in FIGURE 1. The ends of the endless cord are such that they are substantially closely spaced apart by reason of the

2

ends of the rope or cord 30, 32, as shown in FIGURE 2, are such that there is a coupling or steel sleeve 34, 36 located thereon for attaching to the ends thereof a hook 38, 38 on the ends of each of the steel sleeves 34, 36. 5 The hooks are made of steel wire, and hold each of the ends together, as shown in FIGURE 2. The overall length of the steel sleeves 34, 36, together with their interconnecting hooks 38, 38, are such that the entire non-polishing length thereof is substantially less than two inches and in most cases is no more than a maximum length of approximately two inches. This provides for allowing one end of the outgoing rope or cord 20 that is polishing through the die 22 to act as a guide to the trailing end of the cord as it enters the top side of the hole of the die, as shown in hole 26 in FIGURE 1.

By reason of the substantially shortened connection means 30-38, there is provided a maximum amount of cord length for polishing the holes of the die 22, and there is also provided means by which the die is accurately polished so that any whiplash or stray connecting means of elongated character would not provide any vibratory and undamped motion as it passes through the die holes for scarring or otherwise damaging the polished holes that have been completed by the previous passage 25 of the rope or cord 20 therethrough.

Thus it is apparent that the invention is accomplished by the substantially shortened connection length that is provided in connecting the ends of the cord together, as shown in FIGURE 2. In FIGURE 3, there is shown that 30 a plurality of cord ends may be connected together with the adjacent ends of the respective cords so that they are not in substantial coincidence as they pass through in time in the openings or holes 24, 26 of the die 22. The invention thus is shown to provide an improved arrangement and method of operation of rope polishing of compression dies as used in various industries. The invention is an improvement over the use of substantially long cable connections between ends of cords, which connections have been at least in some cases two feet to 26 inches 40 in length, and by the practice of the present invention substantially improved polishing and production of polished compression dies has been achieved. Also the invention provides a polished die as well as a polishing cord 20 in which the cord is not damaged as it is continuously passed through the holes of the die. The absence of total destruction of the ends of the cord is a significant improvement over the polishing as practiced in the prior art.

Additional embodiments of the invention in this specification will occur to others and therefore it is intended that the scope of the invention be limited only by the appended claims and not by the embodiment described hereinabove. Accordingly, reference should be made to the following claims in determining the full scope of the 55 invention.

What is claimed is:

1. Apparatus for polishing at least one of a plurality of closely spaced bore holes comprising a plurality of looped cords adapted to pass through said holes, a pair of spaced pulleys forming a common support for the opposed portions of said looped cords, means for hooking the ends of the cords to each other to provide a short coupling length between the ends thereof, and means for driving the pulleys to pass said cords through said holes.
2. Apparatus for polishing at least one of a plurality of closely spaced bore holes comprising a plurality of looped cords adapted to pass through and be spaced by said holes, a pair of spaced pulleys forming a common support for the opposed portions of said looped cords, said cords being slidable axially on said pulleys to vary the spacing therebetween, means for driving one of said

pulleys to simultaneously pass said cords through said holes, and connecting means on each end of said cords forming a substantially short connection between mutual and adjacent ends of said cords wherein said connection means is substantially short in length.

3. Apparatus for polishing a plurality of closely spaced bore holes comprising a plurality of looped cords adapted to pass through and be spaced by said holes, at least a pair of spaced pulleys forming a common support for the opposed portions of said looped cords, the cords being slidably and axially mounted on said pulleys to vary the spacing therebetween, means for driving the pulleys to pass the cords between said holes, and hook means on the ends of each of said cords for connecting with the hook on the other end of said cords mutually therewith to form a substantially short connection that is readily disconnectable. 15

5
10

4. Apparatus for polishing a closely spaced bore hole comprising a looped cord adapted to pass through said hole, at least a pair of spaced pulleys forming a common support for the opposed portions of said looped cord, said cord being slidable axially on said pulleys and having hook means on the ends of said cord for forming a substantially short connection between the ends thereof to provide the maximum amount of contact between the cord and the hole, and whereas the connection means is substantially short so that essentially no whiplash is provided in the connection means in passing through the hole at high speed and maximum contact of the cord is provided to said hole in polishing thereof.
